LUDWIG GENTZEN, OF MÜLHEIM-ON-THE-RHINE, GERMANY.

METHOD OF INTRODUCING FUEL INTO INTERNAL-COMBUSTION ENGINES.

1,101,271.

Specification of Letters Patent. Patented June 23, 1914.

Application filed November 8, 1911. Serial No. 658,406.

To all whom it may concern:

Be it known that I, LUDWIG GENTZEN, a subject of the German Emperor, residing at Mülheim-on-the-Rhine, Germany, have invented new and useful Improvements in Methods of Introducing Fuel into Internal-Combustion Engines, of which the following is a specification.

This invention relates to a method of introducing fuel into internal combustion engines using fuel of low flashing point of that kind that, on being injected, by means of a charge of atomizing air, into the heated interior of the cylinder, it will not ignite directly. In such cases as is well known, a charge of lighting fuel is used, a small quantity of which is introduced into the cylinder immediately before the introduction of the working charge proper, which charge owing to its easier inflammability, starts the ignition.

The present invention has for its object, in the simplest possible manner, to reduce the quantity of lighting fuel to a minimum. It is based on the observation that the amount of lighting fuel required depends chiefly on its being thoroughly atomized and, if possible, evaporated by means of hot air. To that end, the cylinder is connected to or provided with a preliminary chamber which is normally closed at the rear end, and through which the working fuel and the atomizing air are driven at the moment of the desired ignition. This preliminary chamber is in communication at the point where it opens into the cylinder, with a conduit for the supply of lighting fuel, so that when during the compression period the lighting fuel escapes from the said conduit, it is driven and sprayed into the front part of the preliminary chamber by the air forced out of the cylinder into the said preliminary chamber.

In the accompanying drawing, A represents the working or engine cylinder, b the preliminary chamber closed at the rear end and communicating with a passage controlled by a valve c with the fuel supply. A conduit d for the working fuel merges into the seating of said valve while compressed air is supplied in front of the valve through a conduit e. At its inner end where the preliminary chamber communicates with the cylinder is a cap f provided with several distributing or atomizing holes, with which communicates another conduit g connected

by means of a valve h and conduit i with the lighting fuel inlet pipe.

The working is as follows:—During the compression stroke, preferably during the last portion of the same, lighting fuel is driven, by the opening of the valve h, through the conduit g. Before, however, it can flow into the cylinder, it is driven back and sprayed into the chamber b through the cap perforations by the hot air forced from the cylinder into the said chamber, which, up to that moment, contained only air, with or without a certain amount of working fuel from the last stroke. In the chamber b there is thus collected an inflammable charge of air and lighting fuel. Toward the end of the compression stroke, the valve c is opened, whereupon working fuel passes through d and the atomizing air through e into the chamber b, the said mixture driving the lighting charge in front of it into the cylinder and entering the latter after the said charge. In that way, first the ignition of the readily combustible lighting charge and then of the working charge, take place.

With this process the working fuel itself can be used to provide a lighting charge provided that the parts are properly dimensioned. To that end, the wall k surrounding the conduit b, must be made in such manner, that it will take up sufficient heat from the cylinder, and therefore become sufficiently strongly heated, to gasify the small quantity of the heavy fuel supplied through the conduit g and driven into the chamber b by means of the hot air driven back through the cap f on the compression stroke of the piston in the cylinder. This portion of the working or driving fuel forms with the air so supplied a mixture which can be easily ignited on entering the cylinder, which mixture thus ignites the charge, consisting of a mixture of working fuel with atomizing air which enters subsequently, after the opening of the valve c. In this way, a small portion of the heavy working fuel which otherwise could not be used with auxiliary ignition, as lighting fuel, can be utilized as a lighting fuel because it can be placed in more favorable conditions than the greater portion of the working fuel, as it can take up from the hot wall of the chamber b sufficient heat to gasify it, while the heat of the chamber would be insufficient to vaporize the whole quantity of the working fuel; while it can

be atomized with the small portion of hot air driven out of the cylinder into the chamber, the quantity of which would be insufficient for atomizing the whole charge; 5 finally, because the chamber can hold a small portion of the total required amount of fuel in evaporated state mixed with air, while it would not be possible for it to receive the whole quantity of fuel in such state on account of the excessive dimensions of the 10 chamber that would be required.

A special feature of this process of starting ignition compared to other well known processes in which a preliminary chamber 15 connected to the cylinder is used, is that no burning gases pass through the passages or openings between the cylinder and the preliminary chamber, which is always combined with certain drawbacks. The ignition does 20 not take place in the cap, but in the cylinder, but it cannot light back from the cylinder into the cap or chamber as the subsequent jet of the mixture of the working air and fuel drives the ignited gases farther 25 into the cylinder, and the unlighted gas from the cap or nozzle into the cylinder.

Claims.

1. A process for introducing fuel into internal combustion engines having a preliminary chamber permanently communicating with the interior of the working cylinder, consisting in firstly introducing a small quantity of lighting fuel into the mouth of the preliminary chamber, which charge is 30 forced and sprayed into the interior of the 35

preliminary chamber by the air charge compressed in the cylinder during the compressing stroke, then introducing the working fuel charge mixed with highly compressed air into the rear part of the preliminary 40 chamber, this working fuel charge forcing the lighting fuel charge back into the cylinder, where it ignites itself and ignites the following working fuel charge while the latter enters the cylinder.

2. A process for introducing fuel into internal combustion engines having a preliminary chamber permanently communicating with the interior of the working cylinder, consisting in firstly introducing a small 45 quantity of working fuel into the mouth of the preliminary chamber, which charge is forced and sprayed into the interior of the preliminary chamber by the air charge compressed in the cylinder during the compressing stroke, then introducing the working fuel charge mixed with highly compressed air into the rear part of the preliminary 50 chamber, this working fuel charge forcing the first mentioned charge back into the cylinder, where it ignites itself and ignites the following working fuel charge while the latter enters the cylinder.

In testimony whereof I have signed my name to this specification in the presence of 65 two subscribing witnesses.

LUDWIG GENTZEN.
